UNITED STATES PATENT OFFICE

HARRY D. CLINTON, OF JOHNSON CITY, NEW YORK

WARPING SPOOL

Application filed October 31, 1928. Serial No. 316,211.

This invention relates to textile spools and more particularly to those known as "warping spools" for use in feeding yarn strands onto beam-cylinder or ball warps preparatory to weaving fabrics. It aims to provide spools of a construction adapted to special loading and arrangement for feeding yarn according to the novel method of high-speed warping set forth in my U. S. Patent No. 1,639,927 dated August 23, 1927, for method and means for high-speed warping.

The invention will be best understood upon further description with reference to the accompanying drawings wherein embodiments thereof are illustrated in loading and in feeding positions.

In said drawings:

Fig. 1 is an elevation of one form of spool embodying the invention represented on a winding-spindle for loading;

Fig. 2 is an end elevation of said spool, showing the manner of securing the end of an innermost winding of yarn to the outside thereof;

Fig. 3 is a view representing a pair of the spools as arranged on a creel-rack for uninterrupted feed of yarn according to a special method of high-speed warping;

Fig. 4 is an elevation of a modified form of spool likewise represented on a winding-spindle for loading, the said spindle being shown partly in section;

Fig. 5 is an end elevation of the modified form of spool showing the manner of similarly securing the end of an innermost winding of yarn to the outside thereof; and

Fig. 6 is an elevation showing a detail of the modified spool construction.

In the illustrative embodiments, spools of conventional type are shown respectively comprising a hollow or axially bored barrel 5 having flat disc-like heads 6 secured on opposite ends thereof. This barrel is usually made of wood, while the heads are preferably formed from hard vulcanized-fibre or other composition resisting breakage under rough usage conditions. These heads are rigidly secured to the barrel ends by centrally bored wooden plugs or bushings 7 driven thereinto through central frusto-conical and notched

or ribbed openings in the heads, said plugs being formed with enlarged tapering head-portions resultantly compressed within said apertures in the heads and with reduced glue-coated shank-portions fitting into the bore or receptive counter-recesses formed in the barrel ends.

The head on one end of the barrel in both forms of spool is shown cut through on a substantially radial line to provide a narrow slot-opening 8 in this instance extending from the periphery of the barrel to the periphery of the head. The edges of the head along the cut are advantageously beveled or rounded smoothly as indicated, so as to obviate possibility of cutting the yarn or thread wound onto the spool. In some cases obviously this opening through the head might extend only partially toward the head's periphery or in other words may be formed as a part-length slot or elongate hole instead of the full-length slot shown, but it should always extend inwardly to a point where the inner face of the head contacts with the barrel.

In the form of spool illustrated in Figs. 1 and 2, the plug or bushing 7 at the end holding the slotted head to the barrel is left projecting somewhat beyond the outer face of said head, while the plug at the other end is trimmed off substantially flush with the head at that end. The projecting plug in effect providing an axial extension of the spool barrel is lathed or trimmed to "bottle-neck" form to provide a groove 7^a therein contiguous to the outer face of the head. Said plug is also axially counter-bored to a depth substantially level with the outer face of the head so as to give its projection the form of a ring. In this projection, narrow slits 7^b are shown cut on lines of chords thereacross to a depth preferably less than that of the counter-bore.

Spools of this construction may be loaded and used for general purposes like any ordinary spool, but are specially adapted to unusual loading and arrangement for "magazine" or continuous feed of yarn in high-speed warping operations according to the novel method hereinbefore mentioned, wherein the yarn is drawn off the ends of the spools or in

the line of their axes without rotating the spools.

The manner of loading for this special purpose is illustrated in Fig. 1, wherein a spool of described form is shown applied to a conventional "winding-spindle" 10 on the cup 10^a of which it rests for rotation. In this instance, the spool is placed on the spindle with its slotted head up, but this particular form of spool 10 may be applied with either end or head resting on the spindle cup.

A "traveller-guide" represented by the eyeleted member 11 is shown in the upper position of its movement up-and-down or back-and-forth in parallel relation to said spindle (or to the barrel of the spool thereon) for evenly guiding a thread or strand of yarn onto the spool barrel during rotation with the spindle. From a supply bobbin (not shown), 15 a strand of yarn 12 is shown passing through said "traveller-guide" to and partly around the spool barrel, thence through the slot 8 to the outside face of the spool head and then several times around the projecting plug 7 20 within the groove 7^a where its end is finally engaged in one or more of the slits 7^b in said plug (see Figs. 1 and 2). In thus fastening the end of the yarn, it is advantageously extended across the plug as shown in Fig. 2 so 25 that it may be grasped more easily when desired to disengage or loosen it after the spool is loaded.

As thus extended through and fastened at the outside of one of the spool heads, the end 30 of the yarn is kept from flying around and is also shielded while the spool is rotated for loading through the "traveller-guide", and when the spool has been fully loaded by the 35 yarn windings thereon, the trailing end of its innermost winding will be left extending outwardly from the loaded barrel for connection with the strand on another spool after first 40 loosening to hang free.

In Fig. 3, a pair of the spools loaded as described are represented on a creel-rack in arrangement for "magazine" or continuous feed of the yarn in high-speed warping operations wherein the yarn is drawn off the ends of the spools according to the method described and 45 claimed in my aforesaid Patent No. 1,639,927 dated August 23, 1927. In said figure, the spools (with projecting plug down) are shown engaged over axis-pins 13 inclined to a common "take-off" eyelet 14 equi-spaced from 50 the spool ends, through which the feeding yarn strand is passed to and through a tensioning-device 15 between guide-eyelets 16 and from there to the back comb-member of a warper machine (not shown).

55 In this arrangement, the trailing end of the yarn on the feeding spool is shown connected to the leading end of the yarn on the other or next supply spool, while the trailing end of the yarn on the latter is shown hanging for 60 like connection with the leading end of the

yarn on still another spool to replace the first one. As soon as the yarn on the feeding spool is exhausted, the feed is uninterruptedly transferred to the other spool, and the emptied spool is then replaced by another loaded 70 spool which is similarly connected to the "continuing feed" spool. A plurality of the spools may be arranged and successively connected in this manner, so that a continuous and uninterrupted supply of yarn will be assured during the entire warping operation. 75

The described "magazine" feed arrangement of the spools is possible only when the innermost or trailing ends of the yarn thereon extend outwardly for free connection with the leading end of yarn on other spools, but it is not customary to load spools in this manner. Moreover, the ordinary warping spools are not adapted for loading in this way, and if attempt to do so were made, the necessarily 80 loose end of the yarn would simply slip off the barrel with rotating pull or fly wild until it became entangled with the yarn feeding onto the spool, which would of course result in 85 breakage of the yarn.

The invention therefore provides a special kind or form of spool permitting the innermost end of yarn loaded thereon to be extended and fastened to an outside part for holding it taut and shielded from the winder mechanism during the loading operation and leaving it accessible like the outermost end, after the spool is loaded. Such spools have 90 this particular and important advantage over the ordinary warping spools for the stated purpose, and the added advantage that they will not easily break nor cause injury to the hands in common usage, so that the invention supplies a distinct need in the art. 95

In the modified form of spool illustrated in 100 Figs. 4 and 5, the plugs 7 at both ends are trimmed off substantially flush with the heads, and in place of the projecting plug of the spool first described, two slip-catches 9 are 105 fixed on the outside face of the slotted head. 110 These catches are in this instance provided by small metal washers held close against the head by pins 9^a driven through the head and into the end of the barrel at points adjacent the edge of the plug.

115 Spools of this modified form are likewise usable for general purposes and similarly adapted to the special loading and arrangement for continuous feed described with reference to the first spool. In loading however, it is advisable to apply them to the winding-spindles with their slotted heads down or resting on the spindle cups to prevent possible injury to the hand in grasping to remove from the spindle while still rotating.

120 The manner of loading the modified form of spool is illustrated in Fig. 4 wherein the slotted head is shown resting on the spindle cup with the slip-catches 9 encompassed by 125

the latter. In this instance the "traveller-guide" 11 is in the lower position of its movement and the loading strand of yarn 12 is shown passing therethrough to and partly 5 around the spool barrel, thence through the slot 8 to the outside face of the spool head and then over the latter to the two slip-catches around which its end is looped several 10 times against slippage (see Fig. 5). Otherwise, the special loading of the spool is the same as the other, and these spools when loaded are arranged for "magazine" feed of the yarn in exactly the same way as herein-before described with reference to said other 15 form of spool.

In spools of the modified form having heads of a diameter substantially greater than the supporting cup of the winding spindle, the slip-catches may be placed near the peripheral edge of the head beyond the edge of said cup, rather than close to the plug so as to be encompassed by the cup as herein shown.

Obviously, spools adapted for loading with the innermost end of the yarn thereon extending outwardly from the barrel may be made in various forms without departing from the spirit and scope of this invention, the essential purpose of which is to provide for fastening the yarn end to the outside of the spool without extending it across the inner face of either head and by means which will not allow entanglement during loading nor cause breakage of the yarn or other spools when put in use and thrown about. 30 35 Accordingly, while certain restrictions are necessarily imposed, it is not intended that the invention shall be limited by the appended claims to the specific construction shown and described.

40 Having thus described my invention, what I claim as new and desire to secure by Letters Patent of the United States is:

1. In a spool embodying a barrel having disc-like heads of a diameter substantially 45 greater than its barrel, means adapting the end of the innermost winding of yarn strand thereon to be extended outwardly to and fastened at the outer side of one of its heads without passing such end across the inside 50 face of such head; said means including a narrow radial slot through said one of the heads from a point in the latter's periphery to a point of its juncture with the barrel, a short axial extension of the barrel beyond 55 the face of said head, a peripheral groove in said extension close to the outer surface of said head, and parallel slits across the end of said extension extending to the deepest point of said groove on opposite sides of the 60 spool axis.

2. In a warping spool embodying a barrel having flat disk-like heads of a diameter substantially greater than the barrel, means providing for the end of the innermost winding 65 of yarn on the barrel to be extended outward-

ly to and fastened at the outer side of one of the heads without passing or leading such end across the inside face of the head; said means comprising a narrow radial slit through said one of the heads from a point in 70 its periphery to a point of juncture with the barrel, and a short axial extension of the barrel beyond the face of said head having a peripheral groove in its end and parallel incises thereacross of a depth extending to the 75 deepest point of said groove on opposite sides of the spool axis.

In testimony whereof I affix my signature.
HARRY D. CLINTON.
